UNITED STATES PATENT OFFICE

JOHN F. O'CONNOR, OF CHICAGO, ILLINOIS, ASSIGNOR TO W. H. MINER, INC., OF CHICAGO, ILLINOIS, A CORPORATION OF DELAWARE

COUPLER CONNECTION

Application filed May 12, 1928. Serial No. 277,269.

This invention relates to improvements in coupler connections.

One object of the invention is to provide an efficient coupler connection for railway draft riggings, of rugged design, which may be employed in connection with standard equipment wherein the coupler is mounted for lateral swinging movement through a swivled connection with a pressure-transmitting block which has flat bearing on the front follower block of the railway draft rigging at all times, thus preventing injury to the follower block and coupler and reducing the wear of the parts to a minimum.

Another object of the invention is to provide a coupler connection of the character indicated, wherein the coupler shank is swivled to a pressure-transmitting block, the pressure-transmitting block and the butt end 20 of the coupler shank being provided with co-operating bearing means, including a cylindrical bearing member on one of the parts and a co-operating bearing socket on the other part, adapted to be assembled by inserting the 25 bearing member within the socket in a lateral direction, the parts being maintained in assembled relation by the usual coupler key which extends through the coupler shank and cylindrical member, locking the same against 30 lateral separation but permitting relative swinging movement thereof.

Other and further objects of the invention will more clearly appear from the description and claims hereinafter following.

In the drawings, forming a part of this specification, Figure 1 is a horizontal, longitudinal, sectional view through a portion of the railway draft rigging of a car, illustrating my improvements in connection therewith. Figure 2 is a longitudinal, vertical, sectional view, corresponding substantially to the line 2-2 of Figure 1. And Figure 3 is a top plan view of the inner end of the coupler and co-operating parts, illustrating a 45 different embodiment of my invention.

In said drawings, referring first to the embodiment of the invention illustrated in Figures 1 and 2, 10-10 indicate the usual channel-shaped center or draft sills of a railway car underframe, to which are secured cheek

plates 11 provided with key receiving slots 12 and 13. The striking casting of the railway draft rigging is indicated by 14, and the usual carry iron which supports the coupler shank is designated by 15. A wear plate 16 is disposed between the carry iron member 15 and the coupler shank. A yoke 17 of the horizontal type is disposed between the draft sills, the front ends of the side arms of the yoke member only being illustrated in Figure 1 of the drawings. The usual front follower block is designated by 18 and is provided with a transverse key slot through which the follower key 19 extends. The yoke 17 has the arms thereof provided with slots 20 and 21, which are of the usual form. The follower block key 19 extends through the slots 21 of the yoke and has the outer ends thereof working in the slots 13 of the cheek plates.

In carrying out my invention as illustrated in Figures 1 and 2, I provide, broadly, a coupler A, a pressure-transmitting block B, and a coupler key C.

The coupler A is provided with the usual horn, not shown, from which extends a shank 22. As shown, the coupler shank 22 tapers rearwardly and has the butt end thereof enlarged, the butt end section being cut away centrally to provide spaced, rearwardly extending, inwardly curved arms 23-23. As clearly shown in Figure 1, the inner faces of the arms 23 are curved, as indicated at 24, so as to provide a substantially circular pocket or recess. The free ends of the arms 23 are spaced apart, as shown, and present substantially flat radial end faces 33-33 which, as hereinafter pointed out, act as limiting stops to limit the lateral swinging movement of the coupler. The rear end faces of the arms 23 are also curved, as indicated at 25. These faces are concentric with the curved surfaces 24 on the inner sides of the arms. Immediately adjacent the curved face 25, each arm 23 is provided with a substantially flat, longitudinally extending face 26. Midway between the ends of the enlarged section of the coupler butt, the sides thereof are provided with curved projections 27 which substantially fit between the side arms of the yoke mem-

ber. The faces of the curved projections 27 are concentric with the curved faces 24, so that the coupler may swing between the arms and the yoke without interference.

5 The pressure-transmitting block B comprises a main body portion having a flat transverse end face 28 which bears directly on the front face of the follower block 18. The body portion of the pressure-transmitting block is provided with a forwardly projecting, relatively heavy post 29, having a cylindrical head 30 at the forward end thereof forming a bearing member. The opposite side faces of the post 29 are flat, as indicated 10 at 31—31, and converge forwardly, the same being preferably radial to the center of the pocket in the butt end of the coupler shank. As shown, the cylindrical bearing section 30 fits within the pocket formed by the curved 15 side walls 24—24 of the arms 23, so that the coupler will have pivotal movement on said bearing member. At opposite sides, the front end portion of the pressure-transmitting block proper is cut away, thereby providing 20 concave bearing walls 32—32 on opposite sides of said block, which are concentric with the curved walls 24 of the arms. The inner ends of the arms 23 fit between the cylindrical bearing element 30 and the curved 25 bearing walls 32 of the pressure-transmitting block, so that the arms will bear on both the cylindrical bearing element and the bearing walls 32, the curvature of the end bearing faces 25 of the arms being the same as that 30 of the walls 32.

As shown in Figure 1, the flat end abutment surfaces 33 of the arms 23 are spaced from the abutment faces 31 of the post 29 such a 40 distance that the coupler has the required amount of radial swinging movement. When the coupler has been swung to either side of centered position a predetermined distance, the abutment face 33 at the inner end of one of the arms engages the corresponding 45 side face 31 of the post 29, thus positively limiting the swinging movement of the coupler.

Although the pressure-transmitting block B has been described as a member separate 50 from the coupler shank, it in fact forms a separable butt end member of the coupler shank, the coupler shank being of two-part construction, the parts of which have swiveled connection, so that the coupler butt will 55 not rock on the follower member of the railway draft rigging but radial swinging movement of the coupler is permitted.

The coupler A is connected to the yoke 17 and the sills of the railway draft rigging by 60 the key C, which is of the usual form. In order to accommodate the key, the enlarged section at the rear end of the coupler shank is provided with a transverse key receiving slot 34 which intersects the pocket formed 65 by the curved walls 24 of the arms 23. The

cylindrical bearing section 30 and the front end portion of the post 29 of the pressure-transmitting block B are also provided with a slot 35 which is adapted to accommodate the coupler key C, the slot 35 registering with the slot 34 when the pressure-transmitting block is assembled with the coupler shank. The key C extends through the aligned slots 70 34 and 35, the key receiving slots 20 of the arms of the yoke and the key receiving slots 12 of the cheek plates of the draft sills. As shown, the key C is headed at one end and is provided with a retaining element of well known form, indicated by 36, at the other 75 end.

In assembling the parts of my improved coupler connection as illustrated in Figures 1 and 2, the cylindrical bearing element 30 of the pressure-transmitting block and the arms 23 of the coupler shank are inter-engaged by bringing the bearing element 30 in alignment with a pocket provided between the arms 23 and then passing the same into said pocket and the inner ends of the arms 23 into the space between the cylindrical bearing element and the walls 32 of the pressure-transmitting block B by moving the coupler shank and the pressure-transmitting block laterally toward each other in a vertical direction until the key receiving openings 34 and 35 of the coupler shank and the pressure-transmitting block B are brought into alignment. When the parts have been thus assembled, the coupler shank is connected to the pressure-transmitting block for pivotal movement so that the coupler shank may swing laterally. When the parts have been thus far assembled, the key C is inserted through the openings in the draft sills, the arms of the yoke and the aligned openings 34 and 35 of the coupler shank and pressure-transmitting block B. As will be evident, when the key has been thus inserted, the parts A and B are held against separation in a vertical direction, thus holding the coupler shank and pressure-transmitting block positively assembled. When it is desired to remove the pressure-transmitting block B from the coupler shank, the key C is withdrawn, thereby permitting vertical separation of the bearing elements of the swiveled connection between the inner end of the coupler shank and the pressure-transmitting block B.

In the operation of my improved coupler connection, the shank of the coupler has a swiveling movement on the bearing member 30 and the bearing walls 32 of the pressure-transmitting block, the lateral swinging movement of the coupler being limited by engagement of the end abutment faces 33 of the arms 23 of the coupler shank with the side faces 31 of the post 29 of the pressure-transmitting block B, as hereinbefore pointed out. When a draft action is applied to the coupler, the yoke 17 is pulled forwardly through the 125 130

medium of the key C, thereby compressing the shock absorbing means which is disposed within the yoke, against the front follower block 18 which is held by the key 19. During 5 this time, free swinging movement of the coupler is permitted without effecting any swinging movement of the block B and the front follower block 18. As shown, the slot 34 of the shank of the coupler fits the key and the 10 slot 35 of the block is wider than the key to permit of the swinging movement of the key. In a buffing action, the coupler is forced inwardly, thereby forcing the pressure-transmitting block B inwardly also against the 15 front follower 18, the follower 18 acting against the usual shock absorbing means to compress the same. As the coupler key fits the shank snugly, the key swings in unison with the coupler shank and acts to center the 20 coupler through the pulling action of the yoke.

Referring next to the embodiment of the invention illustrated in Figure 3, the same comprises, broadly, a coupler D, a pressure-transmitting block E swiveled thereto, and a 25 coupler key F. The coupler key F is connected to a yoke in the same manner as the coupler key C illustrated in Figures 1 and 2, and the pressure-transmitting block E bears directly 30 on the flat front face of a follower block similar to the follower block 18 hereinbefore described.

The butt end of the coupler shank D is provided with a cylindrical enlargement 40 35 having a central pocket 41 which is open at the top and provided with a bottom wall 42. The vertical wall of the pocket 41 is of true circular form and the pocket is adapted to receive a cylindrical enlargement 43 formed 40 on the post section 44 projecting from the pressure-transmitting block E. As clearly shown in Figure 3, the central portion of the cylindrical enlargement at the rear end of the coupler shank is cut away, as indicated at 45, 45 to accommodate the post section 44. The cut away section 45 is considerably greater than the width of the post, thereby providing flat abutment faces 46—46 spaced from the sides of the post. The abutment faces 46 limit the 50 radial swinging movement of the coupler in the same manner as the corresponding abutment faces at the inner ends of the arms 23 of the coupler A, hereinbefore described. The cylindrical bearing element 43 substantially fits the pocket 41 so that the coupler D is accurately guided in its swinging movement. The bearing elements 43 and 40 of the pressure-transmitting block and the coupler shank are held assembled in a similar manner 55 to the corresponding parts hereinbefore described in connection with the embodiment of the invention illustrated in Figures 1 and 2, the key F extending through aligned slots in the bearing member 43 and the inner end of the coupler shank, and having its opposite

ends accommodated in the usual key receiving slots of the yoke and center or draft sills. As shown in Figure 3, the key receiving slot of the pressure-transmitting block also extends into the post 44 and the front end portion of the block E proper. 70

In assembling the parts of the swiveled connection as illustrated in Figure 3, the bearing member 43 is inserted through the top of the pocket of the coupler shank and forced downwardly within said pocket until the bearing member 43 rests on the bottom wall of the pocket, and the key receiving slots of the bearing member 43 and the coupler shank are brought into alignment. The coupler key is then inserted through the aligned key receiving openings of the bearing members, the yoke arms and the draft sills. 75 80

While I have herein shown and described what I consider the preferred manner of carrying out my invention, the same is merely illustrative and I contemplate all changes and modifications which come within the scope of the claims appended hereto. 85

I claim:

1. In a railway draft rigging including spaced center sills, a yoke member having side arms, a front follower having a keyed connection with the yoke and shock absorbing means within the yoke co-operating with said follower, the combination with a coupler having a one piece shank; of a pressure-transmitting block pivoted to the shank of the coupler, said block bearing on the front follower, said pivoted connection including interengaging bearing means on the coupler shank and pressure-transmitting block having cooperating cylindrical engaging surfaces, adapted to be inter-engaged by relative lateral movement of said shank and pressure-transmitting block toward each other in a direction lengthwise of the axis of the pivoted connection; and a key for connecting the coupler shank to the yoke, said key extending through the coupler shank and block 100 105 and engaging abutment means on said block and shank disposed transversely with respect to the pivotal axis of said connection to prevent relative separation of said block and shank in a direction lengthwise of said axis. 110 115

2. In a railway draft rigging including a yoke member and a front follower co-operating therewith, the combination with a coupler; of a pressure-transmitting member bearing on said front follower and having a swiveled connection with the coupler shank providing for lateral swinging movement about the axis of the swiveled connection, said swiveled connection including inter-engaging, separable bearing elements on said shank and member, respectively, said bearing elements being assembled and inter-engaged by relative movement thereof axially of said swiveled connection; and a coupler key for connecting the coupler shank to the yoke, said 120 125 130

key having shouldered engagement with the coupler shank and member to maintain said bearing elements against separation in a direction axially of said swiveled connection.

5. 3. In a railway draft rigging including a yoke member adapted to enclose a shock absorbing means and a front follower having a key connection with said yoke member, the combination with a coupler; of a pressure-transmitting member bearing on the follower and having a swiveled connection with the shank of the coupler, said swiveled connection including inter-engaging bearing elements formed integral with the coupler shank and pressure-transmitting member, respectively, one of said bearing elements being in the form of a substantially cylindrical member and the other being in the form of a socket accommodating said cylindrical member, said cylindrical member being inter-engaged with said socket by relative movement toward each other in a direction axial of said bearing members; a coupler key connecting the coupler shank to the yoke, said key also extending through aligned slots in said coupler shank and cylindrical bearing member and locking the bearing member to said socket, against separation in said axial direction.

4. In a railway draft rigging including a yoke member and a follower disposed within the yoke, the combination with a coupler provided with a shank member; of a detachable butt member swiveled to said shank member, the swiveled connection between said members including a cylindrical bearing element on one of said members and a socket provided on the other member, within which said cylindrical bearing element is disposed, said socket member and cylindrical bearing element being provided with transverse, aligned key receiving slots; a coupler key extending through said slots for connecting the coupler to the yoke and holding said swiveled connection against separation.

45. 5. In a railway draft rigging including a yoke enclosing a shock absorbing mechanism and a front follower within the yoke co-operating with the shock absorbing mechanism, the combination with a coupler provided with a shank member having a lost motion connection with the yoke; of a pressure-transmitting block member having a swiveled connection with the coupler shank member and bearing on the follower, said swiveled connection including spaced, arcuate arms on one of said members and a cylindrical bearing element on the other member, curved bearing walls on said last named member spaced from the outer cylindrical surface of said element, the bearing surfaces of said walls being concentric with the outer bearing surface of the cylindrical element, said spaced arms engaging between said cylindrical element and walls and having concentric bearing surfaces on the inner and outer

sides thereof co-operating with the outer bearing surfaces of said cylindrical element and the curved bearing surfaces of said walls.

6. In a railway draft rigging including a yoke enclosing a shock absorbing mechanism and a front follower within the yoke co-operating with the shock absorbing mechanism, the combination with a coupler provided with a shank member; of a pressure-transmitting block member having a swiveled connection with the coupler shank member and bearing on the follower, said swiveled connection including spaced, arcuate arms on one of said members and a cylindrical bearing element on the other of said members embraced by said arms, said cylindrical bearing element and arms being provided with aligned key receiving slots; and a transverse coupler key connecting the coupler to the yoke and extending through said aligned slots to hold said swiveled connection against separation.

7. In a railway draft rigging including a yoke enclosing a shock absorbing means and a front follower within the yoke co-operating with said shock absorbing means, the combination with a coupler provided with a shank member having a lost motion connection with the yoke; of a pressure-transmitting block member having a swiveled connection with the coupler shank member and bearing on said follower, said swiveled connection including spaced, arcuate arms on one of said members and a cylindrical bearing element carried by a post on the other member, said arms embracing the cylindrical bearing member and engageable with the post to limit the lateral swinging movement of the coupler.

8. A coupler for railway draft riggings including a coupler head provided with a shank having a separable butt end section, said butt end section and shank having inter-engaging connecting elements presenting substantially vertically disposed abutment walls, whereby said shank and butt end may be assembled by relative vertical movement of one toward the other; of a coupler key for connecting the coupler to the draft rigging, said key extending transversely through said inter-engaging elements to hold the same against vertical separation when assembled.

In witness that I claim the foregoing I have hereunto subscribed my name this 10th day of May, 1928.

JOHN F. O'CONNOR.
